HOPPER CAR

Harry M. Pflager, St. Louis, Mo., and Einar G. Hallquist, Wallingford, and William M. Sheehan, Merion, Pa., assignors to General Steel Castings Corporation, Granite City, Ill., a corporation of Delaware

Application June 5, 1933, Serial No. 674,264

11 Claims. (Cl. 105—249)

This invention relates to railway rolling stock and consists in a novel hopper car underframe structure.

Heretofore multiple door hopper cars have been provided with separate hoppers located on each side of the center sill, and due to manufacturing difficulties and for other reasons, these cars have usually been constructed of a plurality of rolled steel parts secured together by riveting or welding. It is a well known fact that rolled steel plates and structural shapes corrode and wear away much faster than steel castings and that a built-up construction frequently has the further disadvantage of the existence of crevices at the joints into which granular materials may sift, which results in corrosion and gradual wearing away of the metal, causing the opening of seams at the joints which, in the absence of continual maintenance, eventually weaken the structure. The provision of separate hoppers on each side of the longitudinal center line limits the capacity of the car and the restricted discharge openings tend to impede the dumping of the lading.

An important object of the present invention is to provide a hopper car underframe structure particularly adapted for integral construction and which shall thereby attain the advantages of increased simplicity, rigidity and durability which such construction possesses over built-up structures.

Another object is to provide improved hopper car construction whereby maximum capacity is attained and discharge of lading is facilitated, and at the same time weight and manufacturing difficulties are decreased.

These objects and others are attained by forming substantially the entire underframe of a single integral casting having a plurality of hoppers extending the full width of the underframe and, in one form of the invention, by entirely eliminating the usual center sill.

In the accompanying drawings which illustrate the invention—

Figure 1 is a top view of a hopper forming underframe.

Figure 2 is in part a side view of the same showing portions of the superstructure, the left half being a longitudinal section on the line 2—2 of Figure 1.

Figures 3, 5, 7, and 8 are vertical transverse sections taken on the corresponding section lines of Figure 1.

Figure 4 is a similar section taken on the line 55 4—4 of Figure 2.

Figures 6, 9, and 10 are partial vertical longitudinal sections taken on the corresponding section lines of Figure 1.

The entire underframe is preferably formed as an integral metal casting including bolsters 44—45, draft sills 42, and diagonals 41, the draft sills, bolsters, and diagonals serving to transmit longitudinal forces, such as buffing and draft shocks, to and from the sides of the underframe.

Between the bolsters are a series of hoppers, each extending substantially the full width of the underframe with their side and end walls constituting the underframe structure intermediate the bolsters. The sloping end walls 46a comprise and constitute intermediate transoms. The hopper side walls 48 extend substantially to the top of the underframe and are doubled over, as indicated at 43, to form box-like structure extending substantially the full length of the underframe between the bolsters and merging with the bolsters and inward extensions of the diagonals 41, the sills 43 being sufficiently heavy to transmit all longitudinal forces on the underframe. The portions 44 of the bolsters outwardly of the beams 41 are substantially of I section, as shown in Figure 20, while the portions 45 thereof between the beams 41 are deepened and of box section, as indicated in Figure 19. Portions 43a of the side sills merging with the inclined side walls 48 of the hoppers are of box section, as shown in Figures 3 and 4, while the portions 43b are of hollow open-sided section (Figure 8). The end portions 43c of the side sills beyond the beams 41 are of right angle section (Figure 7). Thus the portions of the side sills which directly receive transverse forces from the intermediate transoms 46 and 46a are of heavier construction than the portions thereof more remote from the transoms. If desired, however, the entire side sills may be of box or open-sided section, or otherwise shaped, but these must be of sufficient strength to carry all draft and buffing forces and vertical loads on the underframe. The heavy side sills are also well adapted to form reinforcement for the lower edges of the superstructure side walls 41.

In order to resist secondary bending stresses, the bottoms of the hopper end walls are downwardly bellied in shape and preferably of catenary contour, as at 49 in Figure 3, this shaping being particularly desirable where the hopper flooring slopes comparatively gradually, making an angle with a horizontal of 45 degrees or less, as in the present case.

The hoppers have greater capacity than where separate hoppers are provided on each side of the center sill and the hopper opening may be made substantially larger to thereby facilitate and hasten unloading. The discharge of the lading is increased in even greater proportion than the increase in the area of the discharge opening due to the entire elimination of the obstructions at the center of the hoppers since in unloading bulk materials through bottom doors the lading tends to clear first at the center. The metal is most conveniently disposed to withstand all forces to which the various parts may be subjected without at the same time unduly increasing the weight of the structure.

The advantages referred to may obviously be attained substantially in structures varying in certain details from the embodiment described and the exclusive use of all modifications as come 20 within the scope of the appended claims is contemplated.

What is claimed is:

1. In a hopper car underframe, a series of longitudinally disposed hoppers with side walls, said walls being folded upon themselves at their tops to form underframe main force transmitting elements.
2. In a hopper car underframe structure, a hopper side wall with a portion at its upper extremity folded upon itself to form a hollow sill structure having at least three sides and sufficiently substantial to transmit draft and buffing forces applied to the underframe.
3. In a hopper car underframe, a hopper extending from side to side of the underframe and unobstructed at the center, said hopper having a side wall with its upper portion folded upon itself to form a substantial underframe side sill element for transmitting longitudinal forces.
4. A hopper car integral cast underframe structure including a plurality of hoppers having side walls, and a cross tie extending across the underframe between said hoppers, the upper portions of said side walls being folded upon themselves to form substantial side sill structure, the folded over extremities of said side walls adjacent said cross tie merging with portions of said walls spaced from said extremities to form box section sill structure for receiving forces directly from said cross tie.
5. In a hopper car underframe, bolsters, side sills, longitudinally discharging hoppers, a transverse member extending in a direct line between the upper portions of said sills, and a transverse member extending in a downwardly bellied curve between the lower portions of the opposing edges of said sills, said members defining an elongated deep hopper discharge opening extending substantially from one side sill to the other and constituting the sole cross member load supporting structure between said sills intermediate said bolsters.
6. In a hopper car underframe, bolsters, side sills, a hopper located between and below the tops of said sills and comprising a member extending in a direct line substantially the entire distance between said sills but sloping longitudinally of the car and forming an end wall of said hopper and another transverse member extending in a downwardly bellied curve substantially the entire distance between said sills but sloping downwardly and longitudinally of the car toward said first mentioned member, the space between the lower edges of said members defining an elongated hop-
- per discharge opening extending substantially from side sill to side sill, said members being formed with sufficient strength to constitute the sole cross member load supporting means between said sills intermediate said bolsters. 5
7. In a hopper car underframe, bolsters, side sills, a series of hoppers between said bolsters, said hoppers being located between and below the tops of said sills and including members extending in a direct line substantially the entire distance between said sills but sloping longitudinally of the car, each of said members forming an end wall of a hopper, said hoppers including other members extending in downwardly bellied curves substantially the entire distance between said sills but sloping downwardly and longitudinally of the car towards said first mentioned members, the space between the lower edges of said first mentioned members and said second mentioned members defining elongated hopper discharge openings extending substantially from side sill to side sill, said members being sufficiently strong to constitute the sole cross member load supporting means between said sills intermediate said bolsters. 10 15 20 25
8. Structure as described in claim 7 in which the upper end portions of adjacent transverse members are joined to each other so that said adjacent members form an angular transverse member extending between said sills. 29
9. In a hopper car underframe, bolsters, a series of hoppers extending between said bolsters, side sills extending between and constituting the sole longitudinal force transmitting elements between the end portions of the end hoppers, said hoppers being located below the tops of said sills and including members extending in a direct line substantially the entire distance between said sills but sloping longitudinally of the car and forming end walls of said hoppers, said hoppers including other members extending in a downwardly bellied curve substantially the entire distance between said sills but sloping downwardly and longitudinally of the car toward said first mentioned members, the spaces between the lower edges of adjacent members defining elongated discharge openings extending substantially from side sill to side sill, said members being formed of sufficient strength to constitute the sole cross member load supporting means between said sills intermediate said bolsters. 35 40 45 50
10. A hopper car underframe structure comprising bolsters and hopper side and end wall plates, said side plates being folded over at their upper edges to form underframe main side sills, said hopper plates constituting the sole horizontal and vertical load carrying members between said bolsters and at least one of said plates being downwardly bowed along its lower edge for strengthening the transverse bracing of the underframe. 55
11. In a hopper car underframe, main transverse end members, and a plurality of hoppers therebetween comprising side and end plates, said side plates being folded to form the underframe main side sills, said hopper plates constituting the sole load carrying means between said end members and the lower edges of said end plates being downwardly bowed to strengthen the transverse bracing of the underframe. 60 65 70 75
